(57) CLAIM

The ornamental design for a swimwear jewelry, as shown and described.

DESCRIPTION

FIG. 1 is a perspective view of the swimwear jewelry.

FIG. 2 is a front elevation view thereof.

FIG. 3 is a rear elevation view thereof.

FIG. 4 is a left side elevation view thereof.

FIG. 5 is right side elevation view thereof.

FIG. 6 is a top plan view thereof; and,

FIG. 7 is a bottom plan view thereof.

The broken lines in the drawings represent portions of the swimwear jewelry that do not form part of the claimed design.
